UNITED STATES PATENT OFFICE

2,243,866

INTAKE SILENCER AND AIR CLEANER

Herbert G. Kamrath, Flint, Mich., assignor to
General Motors Corporation, Detroit, Mich., a
corporation of Delaware

Application November 20, 1935, Serial No. 50,745

3 Claims. (Cl. 181—48)

This invention has to do with air cleaner and silencer assemblies and relates principally to the silencer elements thereof.

In one of its aspects, the invention relates to resonator silencers in which there are included a number of chambers which encircle the main duct and resides in an arrangement of passages for connecting the chambers to the main duct.

In another aspect, the invention relates to means for eliminating the hissing noise due to sound waves of high frequency which usually accompanies the rapid flow of air through a duct and resides in means for eliminating this noise without obstructing the flow of the air through the duct.

For a better understanding of the nature and objects of this invention, reference is made to the following specification wherein there is described the preferred embodiment of the invention which is illustrated in the accompanying drawing.

In the accompanying drawing:

Figure 1 is a view, partly in elevation and partly in section, of an air cleaner and silencer assembly in which my invention is incorporated.

Figure 2 is a top plan view of the assembly shown in Figure 1 with the cover removed.

The air cleaner and silencer assembly which is shown in the drawing includes a cylindrical side wall 10, an upper end wall 11 whose outer edge is seated on an outturned flange on the upper end of the wall 10 and a lower end wall 12 whose outer edge is spun over an outturned flange on the lower end of the wall 10. In the end wall 12, there is formed a central opening which is encircled by an outwardly extending tube 13 which is integral with the wall. In the end wall 11, there is formed a central opening in which there is secured an inwardly projecting tube 14 whose inner end is telescoped within the inner end of the tube 13. The tube 14 is coaxial with and is made of smaller diameter than the tube 13 so that the overlapping portions of the tubes will be spaced apart radially.

The compartment defined by the duct 13—14 and the walls 10, 11 and 12 is divided into upper and lower chambers 15 and 16 by an annular partition 17 whose outer edge is secured in the joint between the outer edge of the wall 12 and the lower end of the wall 10. In the opening in the wall 17, there is secured a tube 18 which encircles the lower end of the tube 14 and extends upwardly into the chamber 15 and downwardly through the chamber 16 into the tube 13 to the same level as the tube 14. The tube 18 is co-

axial with and of larger diameter than the tube 14 but is of smaller diameter than the portion of the tube 13 with which it is telescoped and, consequently, defines with the tubes 14 and 13 5 annular passages 36 and 37 which interconnect the chambers 15 and 16 with the duct 13—14 and with the chambers constitute simple "bottle type" resonators.

The resonator silencer element which has been 10 described is capped by an inverted, generally cup-shaped hood 19. In the side wall of the hood, there are a number of generally rectangular openings 20 and in the top of the hood there are three large sectoral openings 21 which are separated by the legs 22 of a spider which is integral 15 with the hood. The hood is secured to the resonator silencer element and the upper and side walls of the resonator silencer element are secured together by spinning a flange on the lower 20 edge of the side wall of the hood around the flange on the upper end of the wall 10 of the resonator silencer element. The openings 21 in the top of the hood are closed by a cover 23 which is lined with a pad 24 of sound absorbing material, such as felt. The cover 23 is detachably secured to the spider at the junction of its legs 22 by a stud 25 and a wing nut 26.

In the joint between the hood 19 and the resonator silencer element, there is secured the outer 30 edge of a generally hat-shaped element 27 which, because of its shape and the fact that the wall 11 is stepped downwardly just within the wall 10, is spaced well above the upper wall of the resonator silencer element except at its outer edge. 35 In the upper wall of the element 27, there is formed an opening 28 which is coaxial with and of about the same diameter as the tube 14 and bounded by an inwardly and downwardly curved flange. To the inner wall of the element 27, about midway between its top and bottom, there is secured the outer edge of an annular element 30 whose central opening 31 is coaxial with and of about the same diameter as the opening 28 and bounded by a similar inwardly and downwardly curved flange. The element 30 subdivides the recess defined by the element 27 and the wall 11 into recesses 29 and 32 which communicate with the axial passage in the hood and resonator silencer element through the apertures 33 and 34 between the inner edges of the elements 27 and 30 and the wall 11. These apertures, together, with the recesses into which they lead are known as and will be hereinafter referred to as "hiss gaps." 45 50 55

The crown of the element 27 is encircled by

a filter element which consists of inner and outer cylindrical screens 33 and 34 whose interspace is filled with a suitable filter medium 35. The lower end of the filter element is seated in an annular channel in the rim of the element 27 and the top of the hood bears against the upper end of the filter element and holds it in place. It will be noted that the inner wall of the filter element is spaced from the upright wall of the element 27 by reason of the fact that the latter is offset inwardly just after it departs from the rim.

The air cleaner and silencer assembly which is shown in the drawing was designed for installation on an internal combustion engine with the tube 13 connected to the air intake orifice of the carburetor so that it cleans the air which enters the carburetor and silences the so-called "intake" noises of the engine. Although the assembly has been described as if it were to be installed in the upright position in which it is shown in the drawing, it may, of course, be installed "upside down" or with the duct 13-14 extending horizontally or at any inclination.

When the assembly is installed in the described manner and the engine on which it is installed is operating, the suction of the engine draws air from the atmosphere through the openings 28 into the hood 10 and thence, through the filter element 33-34-35, over the element 27 and through the openings 29 and 31 and the duct 13-14 into the carburetor and cylinders of the engine.

The filter element frees the air of foreign matter and the sound absorbing material 24, the hiss gaps 38-29 and 38-32 and the resonators 36-15 and 37-16 eliminate the so-called intake noise of the engine.

While, of course, the presence of the several elements of the assembly which are located on the atmospheric side of the resonators increases the silencing efficiency of the resonators by decreasing the acoustical conductivity of the portion of the passage from the engine to the atmosphere which is located on the atmospheric side of the resonators, essentially, each of the silencing elements has its own job to do. The sound absorbing material 24, of course, eliminates components of the intake noises which are due to sound waves of high frequency.

The components of the intake noises due to sound waves of high frequency which are not sufficiently attenuated by the sound absorbing material are eliminated by the hiss gaps 38-29 and 38-32 whose silencing characteristics depend upon the volumes of the recesses 29 and 32 and the dimensions of the apertures 38 and 39. It will be noted that the hiss gaps 38-29 and 38-32 are differently "tuned," i. e., differ in recess volume and aperture dimensions, so that each of them removes a different component of the intake noises. It will, of course, be understood that the number of hiss gaps which should be employed on any given silencing job, and their recess volumes and aperture dimensions, depends upon the characteristics of the noises which are to be eliminated thereby and, consequently, that, while in the assembly which is shown in the drawing there are incorporated two hiss gaps of particular recess volumes and aperture dimensions, a greater or lesser number of hiss gaps with different recess volumes and aperture dimensions may be found necessary or sufficient in similar assemblies designed for use on other engines.

The components of the intake noises which are due to sound waves of relatively low frequencies

are eliminated by the resonators 36-15 and 37-16 of which each is tuned in the manner set forth in the Wilson application, Serial No. 470,700, filed July 25, 1930, and the corresponding foreign patents, viz., Canadian Patent No. 348,037, British Patent No. 391,180, French Patent No. 720,611 and Italian Patent No. 300,037, so that it responds to and attenuates by resonance certain of the sound waves from which these components of the intake noises result.

I claim:

1. In an appliance of the class disclosed, a member shaped generally like a brimmed hat and imperforate except for an orifice of smaller diameter than its crown in the top of its crown, a member in which there is an orifice joined to the outer and spaced from the inner edge of the brim of the first-specified member with the orifice in it aligned with the orifice in the first-specified member to define a duct through which gases and sound waves may travel, and an annular partition which is disposed between the second-specified member and the top of the crown of the first-specified member with the orifice in it aligned with the orifices in the first and second-specified members and subdivides the recess bounded thereby lengthwise into sound wave attenuating recesses which open radially into the duct.

2. In a silencer, a duct through which gases and sound waves may travel, walls which define with the duct a compartment which encircles and communicates with the duct as a side branch, and a member shaped generally like a brimmed hat and imperforate except for an orifice of smaller diameter than its crown in the top of its crown which is mounted on the compartment and disposed over one end thereof with its brim nearest the compartment, its orifice aligned with the duct and its inner edge spaced lengthwise of the silencer from the nearest end wall of the compartment so that it defines therewith a continuation of the duct and a relatively deep and narrow sound wave attenuating which opens into it radially throughout its circumference.

3. In a silencer, a duct which includes two partly telescoped, radially spaced tubular members through which gases and sound waves may travel, walls which with the duct define a compartment which encircles and communicates with the duct as a side branch through the aperture between the tubular members, a member shaped generally like a brimmed hat and imperforate except for an orifice of smaller diameter than its crown in the top of its crown which is mounted on the compartment and disposed over one end thereof with its brim nearest the compartment, the orifice in it aligned with the duct and its inner edge spaced lengthwise of the silencer from the nearest end wall of the compartment so that it defines therewith a continuation of the duct and a recess which opens into it radially, and an annular partition which is disposed between the top of the crown of the member which is shaped generally like a brimmed hat and the mentioned end wall of the compartment with the orifice in it aligned with the orifice in the top of the crown of the member which is shaped generally like a brimmed hat and subdivides the mentioned recess lengthwise into narrower sound wave attenuating recesses which open radially into the mentioned continuation of the duct.

CERTIFICATE OF CORRECTION.

Patent No. 2,243,866.

June 3, 1941.

HERBERT G. KAMRATH.

It is hereby certified that error appears in the printed specification of the above numbered patent requiring correction as follows: Page 2, second column, line 44, claim 2, after "attenuating" insert the word --recess--; and that the said Letters Patent should be read with this correction therein that the same may conform to the record of the case in the Patent Office.

Signed and sealed this 22nd day of July, A. D. 1941.

(Seal)

Henry Van Arsdale,
Acting Commissioner of Patents.
